US0D1052641S

(12) **United States Design Patent** (10) **Patent No.:** **US D1,052,641 S**
(45) **Date of Patent:** **** Nov. 26, 2024**

(54) **EYEWEAR**

(71) **Applicant:** **SILHOUETTE INTERNATIONAL SCHMIED AG**, Linz (AT)

(72) **Inventor:** **Roland Keplinger**, Linz (AT)

(73) **Assignee:** **SILHOUETTE INTERNATIONAL SCHMIED AG**, Linz (AT)

(**) **Term:** **15 Years**

(21) **Appl. No.:** **29/850,112**

(22) **Filed:** **Aug. 17, 2022**

(30) **Foreign Application Priority Data**

Feb. 17, 2022 (EM) 008861819

(51) **LOC (14) Cl.** **16-06**

(52) **U.S. Cl.**

USPC **D16/315**; D16/335

(58) **Field of Classification Search**

USPC D16/100-101, 300-330, 332-342, 900; D29/106-107, 110

(57) **CLAIM**

The ornamental design for eyewear as shown and described.

DESCRIPTION

FIG. 1 is a perspective view of eyewear showing my new design;

FIG. 2 is a front elevation view thereof;

FIG. 3 is a rear elevation view thereof;

FIG. 4 is a right side elevation view thereof, the left side being a mirror image thereof;

FIG. 5 is a top plan view thereof;

FIG. 6 is a bottom plan view thereof; and,

FIG. 7 is a right side elevation cross-section view thereof taken along line 7-7 in FIG. 5.

The broken lines illustrate features of the eyewear that form no part of the claimed design.

1 Claim, 6 Drawing Sheets
